CLAIM

We claim the ornamental design for a chandelier, as shown and described.

DESCRIPTION

FIG. 1 is a perspective view of a chandelier showing our new design;

FIG. 2 is a front side elevational view of the chandelier, the rear, right and left side elevational views being identical;

FIG. 3 is a top plan view of the chandelier; and,

FIG. 4 is a bottom plan view of the chandelier.

The broken lines shown are for illustrative purposes only and form no part of the claimed design.
